UNITED STATES PATENT OFFICE.

RALPH HAZLETT UPSON, OF AKRON, OHIO, ASSIGNOR TO THE GOODYEAR TIRE AND RUBBER COMPANY, OF AKRON, OHIO, A CORPORATION OF OHIO.

APPARATUS FOR HEATING INFLATING-GAS IN BALLOONS.

1,092,611.

Specification of Letters Patent.

Patented Apr. 7, 1914.

Application filed January 29, 1913. Serial No. 745,026.

To all whom it may concern:

Be it known that I, RALPH HAZLETT UPSON, a citizen of the United States, residing at Akron, in the county of Summit and State of Ohio, have invented new and useful Improvements in Apparatus for Heating Inflating-Gas in Balloons, of which the following is a specification.

This invention relates to apparatus for artificially heating the gas used in balloons, especially of the dirigible type. Briefly, in large balloons, especially of the dirigible type, the volume of gas is, of course, increased by heat and reduced by cold, and hence, when the balloon is in use and the sun shines upon the gas bag of the balloon the latter is heated, thereby expanding the gas and increasing its lifting capacity, and when the sun is obscure the lifting qualities of the gas of the balloon are decreased. It therefore becomes extremely desirable to maintain the temperature of the gas as nearly constant as possible to thereby maintain the vertical equilibrium of the balloon. It will be obvious that as the gas generally employed for inflating balloons is hydrogen, and is highly inflammable, the means for artificially heating the same must be of such a nature as will render the employment thereof absolutely safe.

More specifically, this invention contemplates providing the lower wall of the gas bag or balloon with an opening, preferably surrounded with stiffening elements through which is passed shuttle-fashion an artificial heat-generating instrumentality, so that when shifted into the interior of the balloon and in active operation the gas within the balloon is heated to a proper degree.

The invention further contemplates providing suitable means for closing the opening in the balloon when the heat-generating instrumentality is withdrawn therefrom and also maintaining the closure of the opening during the shifting movement of the heating medium.

With the foregoing and other objects in view, the invention consists in the novel construction, combination and arrangement of parts constituting the invention to be hereinafter specifically described and illustrated in the accompanying drawings which form a part hereof wherein is shown the preferred embodiment of the invention, but it is to be understood that changes, variations and

modification can be resorted to which come within the scope of the claims hereunto appended.

In the drawings in which similar reference numerals indicate like parts in the different figures, Figure 1, is a view in side elevation of the lower wall of a dirigible balloon showing the mechanism by which the heating of the inflating gas is accomplished, a part of the mechanism being shown in section; Fig. 2, is a view in end elevation of the device shown in Fig. 1 with the wall of the balloon in section; and Fig. 3, is a diagrammatic view of a valve mechanism employed.

Referring to the drawings in detail, the reference numeral 1 denotes the lower wall of a balloon, preferably of the dirigible type and which is inflated by a light gas, such, for instance, as hydrogen. The wall 1 is provided with an opening 2 preferably rectangular in outline, and surrounding the opening 2 and within the balloon is a light rigid frame-forming member 3 inclosed by a light metallic casing 4. The member 3 constitutes a beading surrounding the opening 2 in the balloon wall. Outside of the wall of the balloon is a rigid member 5 preferably of wood or some other light material, covered by a coating of thin metal 6 corresponding in contour to the configuration of the member 3 and secured thereto through the medium of bolts or other hold-fast devices 7 which clamp the wall 1 between them for forming a fluid-tight-joint 90 around the opening 2.

The member 5 also forms the upper portion of a frame secured to the balloon frame and also secured at its lower end to the carriage or basket of the balloon. This carriage consists of a plurality of upright bars 8 the lower ends of which are provided with enlargements 10 secured by stays or stay-wires to the frame of the balloon. The uprights 8 are placed at the corners of an imaginary square so as to form an upright rectangular frame. Secured to the lateral pairs of uprights 8, being the ones shown in Fig. 1, and also those shown at the sides in Fig. 2, is a vertical shiftable carriage or elevator consisting of U-shaped side members consisting of uprights 9 carrying guiding members 10 which engage the uprights 8 of the frame and serve to hold the carriage from lateral movement during its ver-

70

tical shifting. The lateral upright members 9 of the carriage are united by integral cross-arms 11 at their lower ends. Extending between the two U-shaped members composed of the members 9 are cross-bars 12, and extending between the uprights 8 of the frame are strengthening cross-braces 13. These members are preferably formed of seamless drawn tubing of light material. Extending across the upper portion of the movable carriage is a floor 14 to which is secured the upper end of a ram 15 reciprocating in a cylinder 16 by which the movement of the ram 15 and floor 14 are controlled. The floor 14 is provided with an upturned marginal flange 17 and is provided at its sides with fixed closure members 18 on the upper ends of which is an upper wall 19 projecting beyond the sides 18 and is further provided near its ends with downwardly-turned flanges 20. Secured to the marginal flange 17 are cross pieces 21 to which are pivotally united, doors 22, extending upwardly and filling the spaces intervening between the flanges 20 and 21 at the ends of the box-like structure mounted on the floor 14. The doors 22 are normally forced outwardly through the medium of springs 23, the function of which will more fully appear later.

Mounted on the floor 14 is a radiator 24 provided with a pipe 25 through which a fluid for heating it is introduced. Positioned immediately in front of the radiator 24, and supported in a bearing 26 therein, is a horizontal shaft 27 on which is mounted a fan 28 and a bevel-gear 29. Secured to the left end of the horizontal shaft 27 is an L-shaped housing 30 the lower leg of which is provided with an aperture in which is fixed the upper end of a sleeve 31. Mounted in the sleeve 31 is an upright shaft 32, to the upper end of which is secured a bevel-gear 33 meshing with the bevel-gear 29. The lower end of the shaft 22 is rotatably mounted in a step 34 mounted on a cross-bar 35 (see Fig. 2) extending between the two cross-arms 11. Splined on the shaft 32 is a belt-receiving pulley 36 which is held against movement during the vertical reciprocation of the carriage through the medium of an arm 37 secured to one of the uprights 8. Extending across the upper portion of the box-like structure or casing formed by the sides 18 and the doors 22 when closed is a diaphragm of foraminous or reticulated material 38. Vertically shiftably mounted in a bearing 41 in the floor 14 of the carriage, is a rod 42 on the upper end of which is a head 43 from which extend ropes, cables or other flexible members 44 to anchorages on the inner faces of the doors 22 and the flexible members 44 in their passage from the head 43 to the doors 22 pass over a double pulley 45 secured to the

under face of the upper wall 19 of the box-like structure of the carriage. Depending below the floor 14 is a bracket 46 in which is a bearing 47 for the lower end of the upright rod 42. To the lower end of the rod 42 is secured an eye or other suitable anchorage 48 to which is connected a wire or rope 49 passing around a pulley 50 to a lever within the grasp of the operator of the balloon. Depending from the floor 14 of the carriage and in open communication with the interior of the box-like structure above the floor is a pipe 51 for a purpose to be later described.

In Fig. 3 is shown a diagrammatic view of the valve mechanism employed for controlling the device and it consists of a valve-casing 52 provided with an inlet 53, having a check-valve 54, and the casing is further provided with an exhaust 55. Also communicating with the interior of the valve-casing is an inflating pipe 56 communicating with gas under pressure in the balloon. Within the valve-casing is a valve 57 the object and function of which will appear later.

Briefly, the operation is as follows: Under normal conditions the box-like structure above the floor 14 is lowered so that the projecting portions of the upper wall 19 will rest on the upper face of the metallic reinforce surrounding the ring 5 and thereby seal the opening 2 in the lower wall of the balloon in doing which the doors 22 will be in their closed position, as shown in full lines in Fig. 1. When it is desired to raise the temperature or heat the gas within the interior of the balloon the valve 57 is turned into the position shown in full lines in Fig. 3, thereby permitting the gas from the balloon to pass through the inlet conduit 56 to the valve casing 52 and from thence upwardly through the pipe 39 into the interior of the box-like structure above the diaphragm 38 from whence it passes slowly downwardly driving out the atmospheric air contained in the box, through the exhaust 51 and into the casing 52 from whence it escapes through the exhaust 55. After this has been accomplished a fluid is admitted to the interior of the cylinder 16 of the ram 15 which causes the upper box-like portion of the margin to move shuttle-wise into the cavity of the balloon in doing which the doors 22 will be in their closed position, thereby preventing the gas within the balloon from escaping through the opening 2. The upward movement of the carriage is kept up until the floor 14 engages the under face of the metallic covering of the stiffening member 5 sufficiently to form an approximately fluid-tight joint therewith. The doors 22 are then opened by permitting the rod 42 to rise, allowing the doors to swing outwardly, as shown in dotted lines in Fig. 1 until they rest upon the lower wall of the

balloon, in doing which the outward movement of the doors is assisted by the springs 23. The fan 28 is then operated, driving the gas within the balloon through the box-like structure which is then open at both ends so that enough gas in the balloon is passed through this passage way and heated through the medium of a radiator 24. When the temperature of the fluid within the balloon has been raised sufficiently the doors are closed through the medium of the flexible member 49 and the box-like structure on the carriage is lowered to its original place and the gas within the box-like structure is removed by reversing the position of the valve 57 to bring it into the position shown in dotted lines and air is passed through the check valve 54 in the inlet 53 causing the air to pass upwardly through the pipe 51 into the cavity of the box-like structure driving the gas upwardly and outwardly through the opening 40 down through the pipe 39 into the valve-casing 52 from whence it escapes through the outlet 55.

25 I claim:—

1. A balloon provided with an opening in a wall thereof, reinforcing members surrounding said opening, a heat-generating instrumentality capable of being projected through said opening into the interior of said balloon for heating the fluid therein, and means for maintaining a fluid-tight closure for said opening irrespective of the position of said heat-generating instrumentality.

2. A balloon provided with an opening in a wall thereof, a reciprocating carriage positioned adjacent to said opening, a heat-generating instrumentality mounted on said carriage and adapted to move shuttle-fashion through said opening and arranged when shifted into a position within the interior of said balloon to heat the fluid contained therein.

45 3. A balloon provided in a wall thereof with an opening, a stiffening medium surrounding said opening, a reciprocally-moving carriage, guiding means for said carriage, a heating instrumentality mounted on said carriage adapted to move shuttle-fashion through said carriage for heating the contents of said balloon.

55 4. A balloon, a wall whereof is provided with an opening, a reciprocally-moving carriage positioned adjacent to said opening, a heating medium mounted on said carriage and adapted to move shuttle-fashion through said opening, and a current-creating medium on said carriage for bringing the fluid contained in said balloon into contact with said heating medium.

60 5. A balloon provided with an opening in a wall thereof, a reciprocally-movable carriage positioned adjacent to said opening, guiding means for said carriage, a heat-gen-

erating instrumentality mounted on the said carriage and adapted to move shuttle-fashion through said opening into said balloon for heating the interior thereof, a current-creating medium on said carriage for creating a current of fluid in said balloon past said heat-generating instrumentality for heating said fluid, and means on said carriage to close the opening in said balloon when said heat-generating instrumentality is removed from the interior of said balloon.

6. A balloon provided with an opening in a wall thereof, a reciprocally-movable carriage positioned adjacent to said opening, a casing on said carriage and adapted to move shuttle-fashion through said opening, a heat-generating instrumentality in said casing adapted to heat the contents of said balloon when moved into the interior of said balloon through said opening, said casing provided with a pair of doors, and means for moving said doors into their open or closed position.

7. A balloon provided in a wall thereof with an opening, guiding means positioned adjacent to said opening, a carriage positioned outside of said opening and reciprocally-shifted with respect to said wall, a casing mounted on said carriage, and adapted to move shuttle-fashion into and out of said balloon, a pair of doors on said carriage, means to move said doors to their open position when said casing is within said balloon, and means to move said doors to their closed position during the movement of said casing and also when said casing is positioned outside of said balloon, and a heat-generating instrumentality positioned in said casing for heating the contents of said balloon.

8. A balloon provided with a wall having an opening, a guiding frame positioned adjacent to said opening and outside of said balloon, a carriage reciprocally-mounted on said guiding means outside of said balloon, a casing mounted on said carriage and adapted to move shuttle-fashion through said opening, said casing provided with an upper wall adapted to close said opening when said casing is in its lower position or outside of said balloon, a pair of doors in said casing adapted to remain in their closed position during the movement of said casing and also when said casing is positioned outside of said balloon, means to move said doors to their open position when within said balloon, and a heat-generating instrumentality positioned within said casing adapted to heat the fluid passing through said casing while within said balloon.

9. A balloon provided with an opening in a wall thereof, a rigid member surrounding said opening, a guiding frame secured to said rigid member and positioned outside of said balloon, a longitudinally-shiftable carriage slidable on said frame, a casing car-

ried by said carriage, a heating-instrumentality carried by said casing, a current-creating medium adapted to drive a fluid into contact with said heat-generating instrumentality, a foraminous diaphragm extending across said casing, inlet and exhaust pipes communicating with the interior of said casing on opposite sides of said diaphragm and a pair of doors on said casing 10 capable of being moved to their open position while within said casing, and mechanism to move said doors to their closed po-

sition during the movement of said casing in unison with said carriage and also during the time said casing is outside of said balloon. 15

In testimony whereof I have hereunto set my hand in presence of two subscribing witnesses.
